UNITED STATES PATENT OFFICE.

MICHAEL JOSEPH FLANAGAN AND THOMAS JAMES FLANAGAN, OF TULSA, OKLAHOMA.

VALVE.

1,176,887.

Specification of Letters Patent. Patented Mar. 28, 1916.

Application filed December 29, 1914. Serial No. 879,455.

To all whom it may concern:

Be it known that we, MICHAEL J. FLANAGAN and THOMAS J. FLANAGAN, citizens of the United States, residing at Tulsa, in the 5 county of Tulsa and State of Oklahoma, have invented certain new and useful Improvements in Valves, of which the following is a specification, reference being had thereto in the accompanying drawing.

10 This invention relates to improvements in cut-off valves, more especially adapted for service in pipe lines for conducting oils and the like, and has for its object the provision of a structure of efficient arrangement involving the use of a minimum number of parts, lending to the easy assembling, repair or cleaning, and practical operation of the valve.

The invention broadly comprehends a 20 structure involving a suitable casing provided with a pair of valve seats interposed between the inlet and outlet ends of the casing, associated with a coöperating double faced valve, one member of which is adapted to act as a cut-off for the fluid being transported, and the other member coöperating with a pressure pocket or chamber, so that fluid in said chamber may assist in holding the valve in closed condition, said last mentioned member of the valve being of greater 25 diameter than the cut-off portion of the valve as exposed to the inlet end of the casing, and the valve being of a balanced type as exposed to the outlet end of the casing, 30 in combination with means for relieving the fluid pressure in said pressure pocket or chamber as occasion requires.

More specifically, the preferred embodiment of the invention embraces a casing of 35 integral formation affording suitable valve seats, pressure pocket, and by-passes or ducts, a double valve of integral formation throughout adapted to be inserted or withdrawn through an open top of the casing, 40 and a cover or top for the casing adapted to close the pressure chamber and form communication between the pressure chamber and the relief duct in the casing, combined with a valve carried by the top designed to 45 open and close said relief duct.

That the details of construction and arrangement of parts of our improved construction may be made clear to persons skilled in the art, we have illustrated in the 55 accompanying drawings forming part hereof the above stated preferred embodiment of

the invention, although it will be apparent that alterations and substitutions may be made in the structure as actually disclosed, thereby constituting other embodiments of 60 the invention, without departing from the latter, all as may be in keeping with the hereinafter appended claims.

In the drawings, Figure 1 is a side view of the complete device, and Fig. 2 is a longitudinal vertical sectional view of the same.

Referring more specifically to the drawings, wherein like reference letters designate corresponding parts in the several views, A, represents a casing of globular type terminating at opposite ends in interiorly threaded inlet and outlet portions B and C, respectively, the former being designed to be detachably coupled to a suitable source of supply, such as a tank not necessary to be 75 shown herein, and the latter to be similarly coupled to an outlet piping or the like to meet the conditions of service in connection with which the valve is employed. Interiorly of the casing A, the same is formed with an integral diaphragm or partition having a vertical wall D and a bottom or horizontal portion E, combining to divide the interior of the casing into inlet and outlet portions, as is obvious.

In the horizontal portion E is provided a port F surrounding which on the upper surface of said portion is a valve seat G; and bridging the space above said valve seat, and integral with the upper portion of the wall D as well as integral with the casing A is another valve seat H above and surrounding a similar port J. In the upper portion of the casing A and above said last mentioned valve seat H, we provide a pressure chamber or pocket K, the same being of substantial size, that is, greater in width than the said valve seat and extending through the top of the casing, this pressure chamber being connected to the inlet portion of the casing A by means of an inclined duct L passing downwardly diagonally through the partition D, as illustrated.

M represents a valve stem carrying at its lower end and preferably integrally therewith a valve N adapted to engage the seat G, and at its upper end a similarly formed valve O adapted to engage the seat H, these valve members having suitable guide projections *n* and *o* working in the ports F and J, it being here observed that the exposed upper surface of the valve member O is

considerably larger or greater in diameter than the corresponding exposed upper surface of the valve member N.

P is a cover plate adapted to be removably bolted as at Q to the top of the casing A to close the pressure pocket or chamber K, said cover plate having a centrally located projection p adapted to engage the complementary projection part m on the valve to limit the opening movement of the latter. The cover plate just above referred to is also formed to carry a manually or otherwise operable valve R mounted and packed in a suitable bearing S removably threaded into a correspondingly threaded portion T of the cover plate, said valve being adjustable in its bearing to open from or close onto a seat U in the top surface of the casing A and constituting the mouth of a duct W passing vertically through the upper portion of the casing A and opening at its lower end to the outlet portion of the casing and at its upper end to a passage X formed in the under surface of the cover P and communicating at x with the pressure pocket or chamber K.

From the foregoing description, it will be apparent that the construction therein defined is of an extremely simple and practical nature, and the operation of the same may be stated as follows, to wit: The inlet end of the casing being in communication with a supply tank, and the outlet end coupled with means for conducting the fluid to the point desired, it will be found that, with the proper amount of material in the tank, the double valve will be raised by the weight of the fluid to open the port F, and permit the fluid to feed around the bottom of the casing through the port and outlet end of the casing. It will be seen that when it is desired to actuate the valve M it is necessary to allow the fluid and air contained within the pressure chamber K to pass therefrom through the relief duct W, this duct being controlled by a reciprocating valve. When, however, the supply decreases, or the quantity in the tank lowers to a predetermined level, the valve will close and act as a cut off to prevent the fluid in the outlet returning through the port F, the maintenance of the valve in its closed condition being facilitated by reason of the pressure of the air and water admitted through the port L to the pressure chamber or pocket K above the upper valve, which pressure, with the suction exerted at the outlet end of the casing, will be adequate to hold the valve closed against the pressure of any fluid remaining in the lower part of the casing, it being necessary to open the valve controlling the relief duct allowing the water within the pressure chamber to escape before the main valve is again opened.

When it is desired to feed the fluid through the valve, it is necessary to release the pressure of the water and the air within the pressure chamber K in order to cause the opening of the valve, and under such conditions the valve R is opened to release the water and air confined within the chamber and allow this water and air to pass outwardly through the passage z in the cover and down through the duct W to the outlet portion of the case, at which time the valve M opens.

Should the ports or valves ever become clogged or impaired in any way, it is simply necessary to remove the cover, which will expose the operating end of the valve R for cleaning, etc., and at that time the double valve N—O may be lifted from the seats and withdrawn through the open top of the casing; and similarly the ducts L and W, owing to their approximately vertical dispositions, may be readily cleared of any obstructing matter.

Having thus described the invention, what we claim as new and desire to secure by Letters Patent is:

1. A valve of the character described comprising a hollow casing divided by a partition into inlet and outlet portions, a pair of valve seats interposed between the inlet and outlet portions bordering suitable ports, a cut-off valve having upper and lower portions adapted to engage said seats, the casing being formed with a pressure chamber above the upper valve member communicating with the inlet portion of the casing, and the casing having a relief duct therein between the pressure chamber and the outlet end of the casing, in combination with a valve for closing the duct, and a removable cover for the casing overlying the duct carrying said last mentioned valve.

2. A valve of the character described comprising a hollow casing divided by a partition into inlet and outlet portions, a pair of valve seats interposed between the inlet and outlet portions, a cut-off valve having upper and lower portions adapted to engage said seats, the casing being formed with a pressure chamber above the upper valve member communicating with the inlet portion of the casing, and the casing having therein a relief duct establishing communication between the pressure chamber and the outlet portion of the casing, in combination with a cover for the casing having a recessed portion in its underside adapted to overlie the relief duct in the casing, and a valve carried by the cover for opening or closing the relief duct.

3. A valve of the character described comprising a hollow casing divided by a partition into inlet and outlet portions, a pair of valve seats interposed between the inlet and outlet portions bordering suitable ports, a

cut-off valve having upper and lower portions adapted to engage said seats, the casing being formed with a pressure chamber above the upper valve member communicating with the inlet portion of the casing, and the casing having a relief duct between the pressure chamber and the outlet end of the casing, in combination with a valve therefor, and a cover for the casing overlying the pressure chamber and having a recessed portion in its under face near one side thereof forming a part of the relief duct, the last mentioned valve being carried by the cover.

4. A valve of the character described, comprising a hollow casing divided by a partition into inlet and outlet portions, a pair of seats interposed between the inlet and outlet portions bordering suitable ports, a cut-off valve having upper and lower parts adapted to engage said seats, the casing being formed with an air chamber above the upper valve member communicating with the inlet portion of the casing, the communication between the air chamber and the inlet end of the casing being by means of a port passing

through the upper portion of the partition directly into the pressure chamber, a relief duct consisting of a relatively small bore arranged in one of the solid walls of the casing, and connecting the outlet portion of the casing with the pressure chamber, in combination with a removable cover for the casing having a recessed part therein overlying a portion of the pressure chamber and the relief duct, the recessed portion forming a part of the relief duct to permit the pressure in the pressure chamber to be relieved, and a valve carried by the cover and passing through the recessed portion in the cover and having a reduced end portion for controlling the relief duct.

In testimony whereof we hereunto affix our signatures in the presence of two witnesses.
